US00D729840S

(12) **United States Design Patent**
Lee

(10) **Patent No.:** US D729,840 S
(45) **Date of Patent:** ** May 19, 2015

(54) **DISPLAY SCREEN OR PORTION THEREOF
WITH ICON**

(71) Applicant: **Samsung Electronics Co., Ltd.**,
Suwon-si (KR)

(72) Inventor: **Seung-Myung Lee**, Seoul (KR)

(73) Assignee: **Samsung Electronics Co., Ltd.**,
Suwon-si (KR)

(**) Term: **14 Years**

(21) Appl. No.: **29/456,185**

(22) Filed: **May 29, 2013**

(30) **Foreign Application Priority Data**

Feb. 23, 2013 (KR) 30-2013-0009516

(51) **LOC (10) Cl.** **14-04**

(52) **U.S. Cl.**

USPC **D14/492**; D14/491

(58) **Field of Classification Search**

CPC .. G06F 3/0481; G06F 3/04817; G06F 3/0482

USPC D14/489-495

See application file for complete search history.

(57) **CLAIM**

The ornamental design for a display screen or portion thereof with icon, as shown and described.

DESCRIPTION

The sole FIGURE is a front view of a display screen or portion thereof with icon, showing my new design.

The broken line showing of the display screen is included for the purpose of illustrating environmental structure and forms no part of the claimed design.

1 Claim, 1 Drawing Sheet

U.S. Patent
